(57) **CLAIM**

The ornamental design for a luggage, as shown and described.

DESCRIPTION

FIG. 1 shows a front perspective view of a luggage;
FIG. 2 shows a front elevation view of the luggage of FIG. 1;

FIG. 3 shows a rear elevation view of the luggage of FIG. 1;

FIG. 4 shows a right elevation view of the luggage of FIG. 1;

FIG. 5 shows a left elevation view of the luggage of FIG. 1;

FIG. 6 shows a top view of the luggage of FIG. 1; and,
FIG. 7 shows a bottom view of the luggage of FIG. 1.

The broken lines shown in the drawings illustrate portions of

the luggage and form no part of the claimed design.

1 Claim, 7 Drawing Sheets
